US00D676095S

(12) **United States Design Patent**
Peterson et al.

(10) **Patent No.:** **US D676,095 S**
(45) **Date of Patent:** **** Feb. 12, 2013**

(54) **MONOLITHIC RAIL WITH INTEGRAL
RECEIVER HEIGHT ADAPTER**

(75) Inventors: **Morris Peterson**, Earlysville, VA (US);
Matthew Peterson, Crozet, VA (US);
Charles Robert Overbey, Jr., Deland,
FL (US); **Gary Vance**, Bristol, VA (US)

(73) Assignee: **Ashbury International Group, Inc.**,
Ruckersville, VA (US)

(**) Term: **14 Years**

(21) Appl. No.: **29/401,173**

(22) Filed: **Sep. 8, 2011**

Related U.S. Application Data

(63) Continuation-in-part of application No. 12/251,384,
filed on Oct. 14, 2008.

(51) **LOC (9) Cl.** **22-01**

(52) **U.S. Cl.** **D22/108**

CLAIM

The ornamental design for a monolithic rail with integral receiver height adapter, as shown and described.

DESCRIPTION

FIG. 1 illustrates a perspective, side view of a new design for a monolithic rail with integral receiver height adapter;

FIG. 2 illustrates a right side view of a new design for a monolithic rail with integral receiver height adapter;

FIG. 3 illustrates a front view of a new design for a monolithic rail with integral receiver height adapter;

FIG. 4 illustrates a left view of a new design for a monolithic rail with integral receiver height adapter;

FIG. 5 illustrates a rear view of a new design for a monolithic rail with integral receiver height adapter;

FIG. 6 illustrates a top view of a new design for a monolithic rail with integral receiver height adapter;

FIG. 7 illustrates a bottom view of a new design for a monolithic rail with integral receiver height adapter;

FIG. 8 illustrates an exploded, perspective view of a new design for a monolithic rail with integral receiver height adapter;

FIG. 9 illustrates a perspective, side view of a new design for a right-handed monolithic rail with integral receiver height adapter;

FIG. 10 illustrates a right side view of a new design for a right-handed monolithic rail with integral receiver height adapter;

FIG. 11 illustrates a front view of a new design for a right-handed monolithic rail with integral receiver height adapter;

FIG. 12 illustrates a left view of a new design for a right-handed monolithic rail with integral receiver height adapter;

FIG. 13 illustrates a rear view of a new design for a right-handed monolithic rail with integral receiver height adapter;

FIG. 14 illustrates a top view of a new design for a right-handed monolithic rail with integral receiver height adapter;

FIG. 15 illustrates a bottom view of a new design for a right-handed monolithic rail with integral receiver height adapter;

FIG. 16 illustrates an exploded, perspective view of a new design for a right-handed monolithic rail with integral receiver height adapter;

FIG. 17 illustrates a perspective, side view of a new design for a left-handed monolithic rail with integral receiver height adapter;

FIG. 18 illustrates a right side view of a new design for a left-handed monolithic rail with integral receiver height adapter;

FIG. 19 illustrates a front view of a new design for a left-handed monolithic rail with integral receiver height adapter;

FIG. 20 illustrates a left view of a new design for a left-handed monolithic rail with integral receiver height adapter;

FIG. 21 illustrates a rear view of a new design for a left-handed monolithic rail with integral receiver height adapter; FIG. 22 illustrates a top view of a new design for a left-handed monolithic rail with integral receiver height adapter;

FIG. 23 illustrates a bottom view of a new design for a left-handed monolithic rail with integral receiver height adapter; and,

FIG. 24 illustrates an exploded, perspective view of a new design for a left-handed monolithic rail with integral receiver height adapter.

The broken, dashed lines shown in the various figures depicting embodiments of the invention are included for the purpose of illustrating environment and do not form any part of the claimed design.
